Design No. 4,050, dated May 17, 1870.

DESIGN FOR AN ARROW-GUN.

Fig. 1.

Fig. 2.

*Nineteen.
D. J. Brown
S. A. King, Attorney.*

United States Patent Office.

CHARLES ROBINSON, OF BOSTON, MASSACHUSETTS.

Design No. 4,050, dated May 17, 1870.

DESIGN FOR AN ARROW-GUN.

The Schedule referred to in these Letters Patent and making part of the same.

To all whom it may concern:

Be it known that I, CHARLES ROBINSON, of Boston, in the county of Suffolk and State of Massachusetts, have invented a new and original Design for an Arrow-Gun, termed an arrow-ball; and I do hereby declare that the following is a full and exact description thereof, reference being had to the accompanying drawing making part of this specification,

Figure 1 being a side view of the arrow-ball, with an arrow in it ready for discharging.

Figure 2, a rear view of the same.

Figure 3, a front view of the ball without the arrow.

Like letters designate corresponding parts in all of the figures.

The stock A is of the form of a ball or sphere, with a circular arrow aperture, a, through the center, and trunnions or nails, c c, to which the driving-cord, b b, is attached, situated on opposite sides, equidistant from the arrow-aperture.

The arrow B is of the form shown.

I claim as my invention—

The shape and configuration of parts, as shown, constituting a design for an arrow-gun.

Specification signed by me this 21st day of March, 1870.

CHARLES ROBINSON.
